UNITED STATES PATENT OFFICE.

AUGUST GERARD, OF SOIGNIES, BELGIUM.

MACHINE FOR SHAVING AND FLESHING HIDES AND SKINS.

SPECIFICATION forming part of Letters Patent No. 224,286, dated February 10, 1880.

Application filed July 10, 1878.

To all whom it may concern:

Be it known that I, AUGUST GERARD, of Soignies, Belgium, (a subject of the King of Belgium,) have invented an Improvement in 5 Machine for Shaving and Flesching Hides and Skins, of which the following description, taken in connection with the accompanying plate of drawings, hereinafter referred to, forms a full and exact specification, wherein are set forth 10 the nature and principles of the invention, by which the same may be distinguished from others of a similar class, together with such parts thereof as are claimed as new and are desired to be secured by Letters Patent of the 15 United States.

The nature of this invention consists in providing the machine with a pressure-cylinder, in connection with knives arranged obliquely to each other upon a main or forward shaving- 20 cylinder, with their ends meeting in the center of said cylinder. By such arrangement of the knives the hides are stretched simultaneously with the shaving off of the hair from the hides, 25 said shaving and stretching being accomplished effectually and with great rapidity.

In the accompanying drawings, Figure 1 is a front elevation, and Fig. 2 a side elevation of the same.

The same letters of reference denote like 30 parts in the several figures.

a a is the framing, solidly bolted together and bolted to the floor. Upon this framing is supported a cylinder, *b*, to which are attached the hides by hooks *c*.

35 *d* is a counter pressure-cylinder, which is covered with a thick coating of caoutchouc or other elastic body, in order to yield to the asperities that may present themselves in the hide.

40 *e* is a shaving-cylinder, provided with two series of helicoidal blades, *f*, so arranged with relation to each other that the ends of each blade will terminate in the center of the cylinder. They are mounted, as shown, obliquely

45 with the cylinder, and their edges are blunt for shaving the hair off; but when treating the inside of the skin, or fleshing it, I replace this cylinder by one on which the blades are mounted in a similar manner, and their edges

are made sharp in order to scrape off all fatty 50 or greasy matter. The position of the blades, as described, in relation to each other has the effect to stretch out the hide during the shaving or fleshing operation on the whole surface.

On the shaft *g* of the cylinder *e* is mounted 55 a pinion, *h*, gearing in a wheel, *i*, on the driving-shaft *j*, and the blocks or bearings in which turns the cylinder *e* are so formed as to terminate in two racks, *k l*, which are worked by two toothed segments, *l l*, set in motion by 60 means of the levers *m* and *m'*, which put the pinion *h* in or out of gear, pushing the cylinder *e* to or from the counter pressure-cylinder *d* at will. On the other extremity of the shaft *j* is also mounted a pinion, *n*, gearing in another pinion, *o*, turning on a short shaft secured to the framing *a*, which, in its turn, gears in a wheel, *p*, carrying a pinion, *q*, which gears in another wheel, *r*, on the shaft of which is keyed a small pulley, *s*, over which passes a belt, *t*, 70 which puts it in communication with a larger pulley, *u*, mounted on the shaft *v* of the cylinder *b*, with which it is put in and out of gear by means of the handle or lever *w*.

x is a pipe placed vertically over the machine, and pierced with holes, through which pass jets of water onto the hide during the operation of shaving or fleshing. To the machine is also attached, by means of an elbow-lever, a treadle, *y*, for the purpose of allowing 80 a bar secured to the frame to engage with the lever *m'*.

The working of the machine is as follows: The lever *m* being thrown back, the cylinder *e* is out of gear and removed from the counter pressure-cylinder *d*, and the handle *w* being turned to the left of the operator, the cylinder *b* is liberated, and can be turned by hand, so as to be able to easily fix the hide on the hooks *c*, and this is done in such a manner that just one half of the same is presented to the action of the blades *f*, while the other half remains hanging loose in front of the operator. The handle *w* is then turned to the right and the lever *m* brought forward. The blades *f* come in contact with the hide, from which, on account of their rapid rotation, they remove the hair almost instantaneously. The operator then

throws the machine again out of gear, and, removing the hide from the hooks, replaces it again in the reverse position, so that the second half is operated on in the same manner.

Having thus described my invention, what I claim as new, and desire to secure by Letters Patent, is—

The combination of the pressure-cylinder *d*, shaving-cylinder *e*, rack-bars *kk*, segments *ll*,

levers *mm'*, cylinder *b*, having hook *c*, and pipe *xx*, substantially as shown and described.

In testimony that I claim the foregoing I have hereunto set my hand this 8th day of February, 1878.

A. GERARD.
